(57) **CLAIM**

The ornamental design for a lopper, as shown and described.

DESCRIPTION

FIG. 1 is a left-side perspective view of a lopper according to our new design;

FIG. 2 is right-side perspective view thereof;

FIG. 3 is a front elevation view thereof;

FIG. 4 is a right-side elevation view thereof;

FIG. 5 is a left-side elevation view thereof; and,

FIG. 6 is a top plan view thereof.

The broken lines showing of portions of the lopper are included for the purpose of illustrating environmental structure and form no part of the claimed design.

1 Claim, 6 Drawing Sheets
